UNITED STATES PATENT OFFICE

152,347

DESIGN FOR A MIRROR

Frank A. Marty, Los Angeles, Calif.

Application February 26, 1947, Serial No. 137,172

Term of patent 3½ years

(Cl. D33—9)

To all whom it may concern:

Be it known that I, Frank A. Marty, a citizen of the United States of America, and a resident of the city of Los Angeles, in the county of Los Angeles and state of California, have invented a new, original, and ornamental Design for Mirror, of which the following is a specification, reference being had to the accompanying drawings, forming part thereof.

In the drawings:

Figure 1 is a front elevational view of a mirror, showing my new design,

Figure 2 is a top edge plan view,

Figure 3 is an elevational view of an end view of that shown in Fig. 2;

Figure 4 is a front elevational view of the central portion thereof showing the side wings directed rearwardly; and

Figure 5 is a perspective view showing the mirror folded.

I claim:

The ornamental design for a mirror, substantially as shown.

FRANK A. MARTY.
